PLURAL EXPANSION REFRIGERATION SYSTEM

Homer T. Chappelle, Mineola, Tex.

Application September 14, 1949, Serial No. 115,684

6 Claims. (Cl. 62—115)

1

This invention relates to refrigeration and more particularly to an improved system including a novel evaporator or heat absorbing means by the use of which improved efficiency may be obtained.

It is an object of the present invention to provide a refrigeration system having improved operating characteristics in which the evaporator is of novel construction by means of which improved efficiency may be obtained.

A further object of the invention is to provide an improved refrigeration system employing novel operating characteristics and improved evaporator construction in which a refrigerant is used which is particularly designed for use with the system embodying the present invention.

These and other objects of the invention will become apparent from the following description taken in conjunction with the accompanying drawings, wherein:

Fig. 1 is a diagrammatic layout of one embodiment of the invention;

Fig. 2, a section on the line 2—2 of Fig. 1; and Fig. 3, a section on the line 3—3 of Fig. 2.

Referring to the drawings the system includes a compressor 10 for delivering compressed refrigerant into a discharge line 11 to be received in a condenser 12. From the condenser the liquid refrigerant passes through line 13 into a receiver 14. From the receiver the refrigerant passes through line 15 having a control valve 16 to an expansion valve 17 just before entry into an evaporator 18. From the evaporator a suction line 32 leads back to the compressor 10.

The evaporator consists of a plurality of pairs of tubes 19, 20, 19', 20', etc., two pairs being shown for convenience. It is understood, however, that the invention contemplates the use of a multiplicity of pairs depending upon the capacity of the particular unit. The tubes are connected in series so that the refrigerant flows through each of the tubes individually.

From the expansion valve 17 the refrigerant flows into the tube 19, through the tube, and out its opposite end into the elbow 22 which feeds into a header tube 23. The header tube is disposed transversely of and adjacent the ends of the next pair of tubes 19', 20'. From the other end of the header tube an elbow 24 is connected substantially axially of the tube 20 to a small orifice nozzle 25 positioned within the tube 20. The refrigerant then flows through nozzle 25 into the tube 20 and at its far end out through a tube 26 and into the tube 19' through a small orifice nozzle 27 positioned axially of the tube.

At the opposite end of the tube 19' the refriger-

2

erant is discharged through the elbow 28 into a header 29 from whence it passes through an elbow 30 into the tube 20' by means of a small orifice nozzle 31. At the far end of the tube 20' the refrigerant is discharged into the suction line 32 to the compressor.

The ends of the tubes are provided with jackets 35 and 36 which extend for a small distance from each end of the tube and include the connections 10 at the ends of the tubes. The joints between the jackets and the tubes and the connections are sealed in order that the jackets may be evacuated. Suitable insulation may be provided, if desired, to reduce the transfer of heat from the jacket to the tubes by conduction. For the purposes of evacuation of the jacket, lines 37 and 38 are connected to the jackets 35 and 36 respectively and are joined at a T 39 to a connection 40 provided with a check valve 41 which is placed in the suction line 32. It will be apparent that during the operation of the compressor the jackets 35 and 36 will be under a vacuum corresponding approximately to the suction pressure of the compressor.

Although other refrigerants may be employed, 25 a mixture consisting of carbon tetrachloride, anhydrous methyl alcohol, and ethylene dichloride in the proportion of 20, 60, and 20 by volume respectively is preferred. This mixture is resistant to fire and has a boiling point of approximately 117° F. at atmospheric pressure.

In the operation of the device, the compressor 30 discharges compressed refrigerant to the condenser at a relatively low pressure, which may be on the order of about zero gage. From the condenser the liquid refrigerant drains to the receiver and thence through the line 15 to the expansion valve 17. After passing through the expansion valve the refrigerant goes into the tube 20.

40 In passing through the expansion valve the pressure is reduced to about 12" Hg vacuum under normal operating conditions, the refrigerant being partially gasified in going through the tube 19. At the end of the tube the mixture 45 of gas and liquid refrigerant passes out of the tube through the elbow 22.

The ends of the tubes 19, 20, 19' and 20', etc., the elbow connections and the header tubes 23 and 24 are confined within the jacket 36.

50 As the mixture of liquid and gaseous refrigerant passes from the end of the tube through the elbow 22 it drains into the header 23 which collects the mixture prior to its passage into the next tube. The header may be disposed adjacent 55 or in contact with the next pair of tubes, and

subjected to the temperature prevailing in those tubes. Inasmuch as the refrigerant entering each tube passes through a pressure-reducing nozzle, it follows that correspondingly lower temperatures are attained in the succeeding cylinders comprising the evaporator. It is apparent therefore that heat exchange may take place under these circumstances between the refrigerant passing through a given header and that in the next succeeding pair of cylinders.

From the header the mixture flows upwardly into the elbow 24 and into the nozzle 25 where it is expanded into the tube 20. As a result of the expansion the mixture undergoes a drop in pressure and passes through the tube 20 absorbing heat as it goes.

The refrigerant then passes through the remaining tubes and their nozzles and out of the last tube 20' into the suction line 32. In order that the system operate efficiently the suction in the line 32 should be on the order of approximately 19" Hg vacuum but this may be varied to conform to the characteristics of the particular refrigerant employed.

By reason of the novel construction and arrangement of the evaporator, including the tubes having their ends confined in the jacket under vacuum, the arrangement of the headers, the refrigerant employed, and the order of vacuum under which the system operates, an improved efficiency is attained so that a greater output per unit of input is obtainable than with conventional systems. Furthermore, the jackets are provided with effective insulation at low cost due to the utilization of the compressor for the production of the vacuum therein.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. An evaporator for a refrigeration system comprising a plurality of pairs of elongated cylinders including a last pair, one end of each cylinder providing an intake and the other end a discharge for the particular cylinder, the discharge end of the first cylinder of each pair except said last pair being connected to a cylindrical header disposed transversely of and adjacent the ends of the next pair of cylinders, a connection extending from the header to a nozzle disposed substantially axially of and extending into the intake end of the second cylinder of the pair, a connection from the discharge end of the second cylinder of the pair to a nozzle extending into the intake end of the first cylinder of the next pair, the connection from the discharge end of the second cylinder of the last pair being provided for connection to a compressor suction line, and a connection from the discharge end of the first cylinder of the last pair to a nozzle disposed substantially axially of and extending into the intake end of the second cylinder of the pair.

2. In a refrigeration system, a compressor having a suction line, an evaporator comprising a plurality of pairs of elongated cylinders connected in series, a first cylinder of each pair

being connected by means of an elbow extending from the lower portion of its discharge end to a cylindrical header disposed transversely of and adjacent the extremities of the cylinders, an elbow 5 extending from the header to a nozzle disposed substantially axially of and extending into the second cylinder in the pair, connections being provided to connect the second cylinder of a pair to the first cylinder of the next pair, a jacket 10 housing the ends of the connections at the ends of the cylinders, and means for evacuating substantially all of the air from the jackets in order to produce a substantial vacuum therein.

3. In a refrigeration system, a compressor having a suction line, an evaporator comprising a plurality of pairs of elongated cylinders connected in series, a first cylinder of each pair being connected to a cylindrical header disposed transversely of and adjacent the extremities of 20 the cylinders, means connecting the header to a nozzle extending into the second cylinder in the pair, connections being provided to connect the second cylinder of a pair to the first cylinder of the next pair, a jacket 25 housing the ends of the connections at the ends of the cylinders, and means for evacuating substantially all of the air from the jackets in order to produce a substantial vacuum therein.

4. The structure of claim 3, the last means 30 connecting connections to the suction line of the compressor.

5. A low pressure refrigeration system comprising pump means capable of producing a high order of vacuum; a condenser connected to the pump means; a receiver connected to the condenser; an expansion valve connected to the receiver; an evaporator comprising a plurality of pairs of elongated cylindrical tubes arranged in 35 parallel, connections at the ends of the tubes providing for series flow through the tubes, the connections for a preceding pair being in proximity to a succeeding pair, pressure reducing means being provided for each tube; and a sealed jacket 40 housing the ends of the evaporator tubes and their connections, the jackets having lines extending to the pump means whereby the jackets may be evacuated.

6. In a refrigeration system having compressor 50 means, the compressor means having suction means, an evaporator comprising a plurality of elongated cylindrical tubes connected in series for the passage of refrigerant, each tube having intake means, expansion means in the intake 55 means of each tube for causing a pressure drop in the refrigerant as it enters each of the tubes, sealed jacket means housing the ends of the tubes, and means connecting said jacket means to the suction means for maintaining the jacket means under evacuation by the compressor.
